Primary Examiner — Jasmine Mlinarcik

(57) **CLAIM**

The ornamental design for a hat form, as shown and described.

DESCRIPTION

FIG. 1 is a front, left, bottom isometric view of the hat form; FIG. 2 is a front elevation view of the hat form, the rear elevation view being a mirror image of the front elevation view;

FIG. 3 is a left side elevation view of the hat form, the right side elevation view being a mirror image of the left side elevation view;

FIG. 4 is a top plan view of the hat form; and,
FIG. 5 is a bottom plan view of the hat form.

The shade lines in the figures show contour and not surface ornamentation. The broken lines in the figures show claimed stitching.

1 Claim, 5 Drawing Sheets
